UNITED STATES PATENT OFFICE.

JOHANNA SCOTT, OF PORTLAND, OREGON.

FOLDING TENT.

Application filed August 4, 1924. Serial No. 729,966.

To all whom it may concern:

Be it known that I, JOHANNA SCOTT, a citizen of the United States, and a resident of Portland, county of Multnomah, and 5 State of Oregon, have invented a new and useful Improvement in Folding Tents, of which the following is a specification.

My invention relates to tents and other foldable or knockdown structures especially 10 adapted to be carried upon the running board of an automobile.

In structures of this character it is necessary to provide a dressing enclosure having frame members of relatively short length 15 so that they will ride on the running board and yet the parts must be of such length that the structure is large enough to provide sufficient space to permit a person to stand upright inside the same and also, preferably of sufficient width to accommodate a 20 bed.

Jointed and hinged structures, usually provided, necessitate the expenditure of considerable time in the assembly and knocking 25 down and also are not as rigid as integral members.

The object of my invention, therefore, is to provide a tent in which the frame members are of such length that they can readily 30 be carried on the running board of an automobile, each member being an integral piece of the frame members, being so arranged that a tent of sufficient size can be constructed therefrom, to permit its use as a dressing 35 tent for the occupants of the machine.

A further object of my invention is to provide a tent the frame of which is arranged in units so as to reduce the disconnecting parts to a minimum, thereby to facilitate 40 the setting up of the tent frame and when taken down, condensing the parts of the tent into compact bundles which may be readily packed together for convenient carrying about.

45 A further object is to provide a tent which will be well ventilated and yet which is weather proof, and which is a complete enclosure or screen.

A further object is to provide a tent 50 frame which when assembled forms a rigid support for the covering and which does not depend on said covering for securing its rigidity.

55 I attain these objects by providing a tent frame composed of members connected together in part so that the frame can be

divided and made into compact convenient sized bundles adapted to be carried on the running board of an automobile. The frame consists of a wall portion made of members 60 hinged together in such a manner that they may be folded into two compact bundles and a roof portion made of members hinged together and constituting a third bundle. The members in the wall units are hinged together so that they may be arranged angularly in parallel relationship with each other and when set up provide a sill or bay secured to posts mounted thereon in the corner. The roof unit is preferably made up 65 of units hinged together about a central vertical member and are hinged for parallel and radial arrangement with each other, the structure resembling the radial ribs of an umbrella. I provide the upstanding corner 70 posts and the radial members with engaging means and thus when the roof is in position it serves to strengthen and support the wall units. To further provide a rigid structure I pass a flexible cord or cable about 75 the upper ends of the corner posts which serve not only to strengthen the portions and to hold the wall units in engagement with the roof unit, but also serves as a support upon which the covering for the wall 80 units can be hung. The covering for the roof is placed over the roof frame unit and is either connected or left unconnected thereto.

The details of the foregoing features and 85 others incidental thereto are hereinafter fully described with reference to the accompanying drawings.

In the drawings:

Fig. 1 is a perspective view of my improved tent with portions of the covering shown as broken away, to disclose details of the supporting frame beneath;

Fig. 2 is a fragmentary sectional view through my improved tent and shows how 100 ventilation is provided without providing an opening visible to a person outside of the tent;

Fig. 3 is a perspective fragmentary view illustrating a detail of construction;

Fig. 4 is a perspective view with parts broken away of the roof frame unit;

Fig. 5 is a perspective view with parts broken away of the two wall units the units being shown as disengaged from each other 110 and with the members thereof extended as in operative position;

Fig. 6 is a perspective view of the roof unit shown collapsed; and

Fig. 7 is a perspective view of one unit of the wall units shown collapsed.

- 5 My improved tent is made up with a frame which is preferably adapted to be collapsed into three convenient sized bundle units. Two of these units constitute the wall and one unit the top. One wall unit is
 10 10 made up of the members *a*, *b*, *c* and *d*; *a* and *d* being the up-right corner posts at one side and *b* and *c* being the sills which form the foundation upon which the tent rests. The corner post *a* is held in up-right position
 15 15 by the braces *e* and *e'* and the corner post *d* by the braces *f* and *f'*. The other unit is made up of two corner posts *a'* and *d'* and sills *b'* and *c'*. The corner post *a'* is held up by struts *e*² and *e*³, and the corner post *d'* by struts *f*² and *f*³. All of the struts mentioned consist preferably of flat straps of metal pivoted at one end and provided with a hook which is adapted to fasten about outstanding pins on the sills. The strut *e* is
 20 20 fastened over the pin *g*, the strut *e'* over the pin *g'*, the strut *f* over the pin *g*², the strut *f'* over the pin *g*³, the strut *e*² over the pin *g*⁴, the strut *e*³ over the pin *g*⁵, the strut *f*² over the pin *g*⁶, and the strut *f*³ over the pin
 25 25 *g*⁷. The struts in the order named are pivoted about the pins *h*, *h'*, *h*², *h*³, *h*⁴, *h*⁵, *h*⁶, and *h*⁷. The upper portion of each corner post *a*, *a'*, *d* and *d'* is cut at an angle and provided respectively with upstanding
 30 30 dowels or pins *i*, *i'*, *i*² and *i*³. One end of the member *b* is connected to the member *a* by a hinge *j* and to the member *c* by the hinge *j'*. The member *a'* is fastened to the member *b'* by a similar hinge
 35 35 *j*², the member *c'* is fastened to the member *b'* by the hinge *j*³, the member *c'* is fastened to the member *d'* by the hinge *j*⁴, and the member *d* is fastened to the sill member *c* by a hinge *j*⁵.
 40 40 The lower end of the corner post *a'* is removably fastened to the sill member *b* by a pin *k*, on the end of the member *a'* and which fits in the hole *k'* in the end of the sill member *b*. The corner post *d* is provided
 45 45 with a similar pin *k*² which seats in the hole *k*² provided therefor in the end of the member *c'* to hold said members together.
 50 50 The roof unit is made up with a central section *l* from which a number of radially arranged members *m*, *m'*, *m*² and *m*³ extend and to which they are hingedly attached respectively by the hinges *n*, *n'*, *n*² and *n*³, as shown in Fig. 4. Near the extremity of each radial member *m* and *m*³ inclusive is provided a hole *o*, *o'*, *o*², and *o*³ respectively which is adapted to receive the dowels *i* and *i*³ inclusive.

60 About the wall section of the frame near the inner ends of the corner posts *a*, *a'*, *b* and *b'* I fasten the cable or cord *p*, the

ends of which terminate in rings *p'* and *p*² and I tighten this cable or cord by means of a section of cable or cord *p* which passes through these loops, and by means of which the cord or cable can be tightened to brace the corner posts *a*, *a'*, *d* and *d'*. The covering *q* for the side of the tent is preferably provided with a number of rings *q'* and I pass the cord or cable *p* through these rings. The cord or cable *p* thus serves as a support for the covering. To prevent the cord or cable *p* from slipping downwardly on the corner post I cut a groove in each corner post near the top, in which this cord or cable *p* can seat. The groove *r* is cut in the corner post *a*, and the grooves *r'*, *r*² and *r*³ being cut in the corner posts *a'*, *d* and *d'*, respectively. The end ring *q*² which passes about the cord *p* and holds the covering *q* in place is spaced a slight distance from that end of the covering to which it is fastened and thus there is a portion *q*³ of the covering which is adapted to be folded back upon the remainder of the covering to provide a door, as illustrated in Fig. 3. To hold this portion *q*³ in position I place a number of snaps *q*⁴ along the entire height of the tent as shown in Fig. 1 to provide a continuous enclosure or screen about the sides of the tent.

As can be noted, the grooves *r* to *r*³ inclusive are a substantial distance below the end of the corner posts in which they are respectively cut and thus the top of the covering *q* does not extend up to the top of the corner post, thus providing a substantial opening between the top of the covering and the roof section as shown in Fig. 2. The roof members *m* to *m*³ inclusive are longer than the distance between the corner posts and thus extend some distance outside of the corner posts. The roof covering *s* is mounted over the roof section and is fastened to the same if desired and has a pendent section *s'* about the edge which hangs a substantial distance below the extremity of the radial members *m* to *m*³ inclusive, as shown in Fig. 2. The outer extremities of the members *m* to *m*³ inclusive, extend downwardly outside of the corner posts to a plane substantially aligned with the top of the curtain *q*.

By arranging the roof section in this manner, I prevent the wind from getting a full sweep through the opening which would not only cause a pronounced draft but would also tend to lift the roof from the wall section.

The pendent portion *s'* of the roof covering *s* hangs a substantial distance below the extremities of the members *m* to *m*³ inclusive and thus conceals or screens the opening *t* above the curtain *q* so that this opening is not visible from the outside and also serves to prevent rain from beating into the tent through this opening.

Tents used for camping and adapted to be carried on the running board of an automobile serve not only as dressing chambers for the occupants of the automobile but also are often called upon to serve as a partial shelter at least for the camping bed. The length of the running board determines the length of the members used to make up the frame and thus a tent large enough to entirely enclose a sleeping bed would be too large to be carried conveniently on the running board. It is common custom therefore to make tents of this character with one side open or with one side which is adapted to be lifted upwardly and fastened to the side of the automobile or to some similar object so that head of the sleeping bed can be placed inside of the tent and the remainder of the bed left in the open. By mounting the covering q upon rings which are adapted to slide along the cord or cable p I am thus enabled to entirely remove the covering from one side of the tent by unfastening said snaps q^4 and sliding the covering towards the corner posts a and d . This does not necessitate the lifting of one portion of the tent out of position and may be quickly accomplished without affecting the rigidity and stability of the tent frame.

As hereinbefore mentioned, the tent shown is adapted to be made up in three bundles of convenient size: One bundle of the members which constitute the wall section being illustrated in Fig. 7 and one bundle of the members which constitute the roof section being shown in Fig. 8. With the frame members in this position when it is desired to set up the frame, it is necessary merely to set up each unit by moving said members about their hinged connections and fastening the same in extended position. The member b is moved about its hinged connection until it assumes a right angle with the corner post a , and the strut e can then be hooked about the pin g' . The sill member c can be moved similarly about its connection and the strut e can be fastened over the pin g and the corner post d can then be extended upwardly from the sill member until it assumes a right angle thereto and the strut f can be fastened over the pin g^2 . The corner posts a' and d' can be arranged similarly and fastened in place by the respective struts. The two units can then be fastened together by seating the pin k in the hole k' and the pin k^2 in the hole k^3 , and the struts f and e^2 over the pins g^3 and g^4 respectively. The wall portion of the frame and the sill which forms the foundation therefor are then fully assembled in position. The roof unit can then be opened outwardly like an umbrella and the radial members mounted one upon each corner post with the dowels i to i^3 seating in the holes o to o^3 provided respectively therefor. When the dowels or pins are seated in the holes or sockets provided therefor, the roof section tends to strengthen and support the wall section.

The inner ends of the members m to m^3 respectively are cut at an angle as shown in Fig. 6 so as to permit the members to be extended outwardly so as to form a slope of predetermined pitch, as shown in Fig. 4. When said ends are extended they abut against the central member l and form a rigid roof structure. The angle which these members make with each other is preferably such that the roof will not be very steep and thus members which abut against opposite sides of the central member l , for example the member m and the member m^2 , form substantial continuations of each other.

If one corner tends to collapse inwardly, it is resisted by the opposite corner post through the roof members which extend diagonally between the same. When the dowels are in position in the holes provided therefor in the radial members m to m^3 respectively, the dowels enter the radial member at an angle as shown in Fig. 2 and thus when the cord or cable p is fastened about the corner posts and they are drawn towards each other by the tensioning of the cord or cable, the dowels tend to be seated firmly in the hole so as to prevent the roof from being removed except directly upwardly. This prevents a corner or side of the roof from tending to be lifted by the wind. The cord or cable also tends to prevent any of the corner posts from collapsing outwardly and thus, when the radial members m which tend to prevent the corner posts from collapsing inwardly, they form a frame of extreme strength and rigidity, when the extreme portability is taken into consideration.

The wall covering q being carried by rings q^2 on the cable p is thus fastened in place when the cord or cable p is fitted about the corner posts in the grooves r to r^3 inclusive. If the top covering s is separate from the roof portion of the frame all that is necessary to make a complete tent structure is to place this covering in position. I believe it preferable however to fasten the roof covering directly to the members m to m^3 inclusive, so that it resembles an umbrella and thus the roof covering will be put in place when the radial structures m to m^3 inclusive are mounted upon the corner posts.

I claim:

1. A tent frame comprising two wall-section units each composed of two sill members hinged together for arrangement in parallel and angular relation with each other, a post, hinged at the juncture of said sill members, adapted for parallel and angular adjustment with one of the latter and when arranged in its parallel relation clearing the adjacent end of the upper face of

the other of said sill members, a post hinged to the extremity of the other sill member for arrangement in parallel and angular relation therewith, means for connecting the outer ends of the sill members of the two units, and means for securing the posts in upright position on the sills.

2. A tent frame comprising two wall-section units each composed of two sill members hinged together for arrangement in parallel and angular relation with each other, a post, hinged at the juncture of said sill members adapted for parallel and angular adjustment with one of the latter and when arranged in its parallel relation clearing the adjacent end of the upper face of the other of said sill members, a post hinged to the extremity of the other sill member for arrangement in parallel and angular relation therewith, means for connecting the outer ends of the sill members of the two units, means for securing the posts in upright position on the sills, and a roof frame.

3. A tent frame comprising two wall-section units each composed of two sill members hinged together for arrangement in parallel and angular relation with each other, a post, hinged at the juncture of said sill members adapted for parallel and angular adjustment with one of the latter and when arranged in its parallel relation clearing the adjacent end of the upper face of the other of said sill members, a post hinged to the extremity of the other sill member for arrangement in parallel and angular relation therewith, means for connecting the outer ends of the sill members of the two units, means for securing the posts in upright position on the sills, and a roof frame, the extremities of said roof frame members extend a substantial distance beyond said posts.

4. A tent frame comprising two wall-section units each composed of two sill members hinged together for arrangement in parallel and angular relation with each other, a post, hinged at the juncture of said sill members adapted for parallel and angular adjustment with one of the latter and when arranged in its parallel relation clearing the adjacent end of the upper face of the other of said sill members, a post hinged to the extremity of the other sill member for arrangement in parallel and angular relation therewith, means for connecting the outer ends of the sill members of the two units, means for securing the posts in upright position on the sills, a transverse rope receiving groove provided on each of said posts adjacent to, but spaced from its upper end, a roof frame, the extremities of said roof frame members extending a substantial distance beyond said posts, means for fastening said roof frame on said posts of the wall frame, side curtains adapted to be sus-

pended from ropes located in said grooves of the post, and a roof covering adapted to be supported on said roof frame, provided with pendent side sections extending a substantial distance below the top of said side curtains.

5. A tent frame comprising a wall section composed of two sill members hinged together for arrangement in parallel and angular relation with each other, a post, hinged at the juncture of said sill members, adapted for parallel and angular adjustment with one of the latter, and a post hinged to the extremity of the other sill member for arrangement in parallel and angular relation therewith.

6. A tent frame comprising a wall section composed of two sill members hinged together for arrangement in parallel and angular relation with each other, a post, hinged at the juncture of said sill members, adapted for parallel and angular adjustment with one of the latter, a post hinged to the extremity of the other sill member for arrangement in parallel and angular relation therewith, and means for securing the posts in upright position on the sills.

7. A tent frame comprising two wall-section units each composed of two sill members hinged together for arrangement in parallel and angular relation with each other, a post, hinged at the juncture of said sill members, adapted for parallel and angular adjustment with one of the latter, a post hinged to the extremity of the other sill member for arrangement in parallel and angular relation therewith, means for connecting the outer ends of the sill members of one unit with the post of the other unit, and means for securing the posts in upright position on the sills.

8. A tent frame comprising two wall-section units each composed of two sill members hinged together for arrangement in parallel and angular relation with each other, a post, hinged at the juncture of said sill members, adapted for parallel and angular adjustment with one of the latter, a post hinged to the extremity of the other sill member for arrangement in parallel and angular relation therewith, means for connecting the outer ends of the sill members of the two units, means for securing the posts in upright position on the sills, a transverse rope receiving groove provided on each of said posts adjacent to, but spaced from its upper end, a roof frame, side curtains adapted to be suspended from ropes located in said grooves of the post, and a roof covering adapted to be supported on said roof-frame, provided with pendent side sections extending a substantial distance below the top of said side curtains.

9. A tent frame comprising two wall-section units each composed of two sill mem-

- bers hinged together for arrangement in parallel and angular relation with each other, a post, hinged at the juncture of said sill members, adapted for parallel and angular adjustment with one of the latter, a post hinged to the extremity of the other sill member for arrangement in parallel and angular relation therewith, means for connecting the outer ends of the sill members of the two units, means for securing the posts in upright position on the sills, a roof-frame comprising members hinged together for parallel and radial arrangement, and means for fastening said roof-frame on said posts of the wall frame.
10. In a foldable tent, a frame consisting of corner posts each connected to the others at their lower ends, a roof section made of members hingedly connected to each other at one end and extending radially from said
15. point of connection, co-operating engaging means carried by the upper end of said corner posts and said radial members, and having a flexible cord fastened about said corner post tending in part to hold said engaging means in co-operative relation. 25
11. In a foldable tent, a frame consisting of corner posts each connected to the other at their lower ends, a roof section made of members hingedly connected to each other at one end and extending radially from said point of connection, co-operating engaging means carried by the upper end of said corner posts and said radial members, having a flexible cord fastened about said corner post tending in part to hold said engaging means in co-operative relation, a side covering carried by said flexible cord, and a roof covering carried by said radial members. 30 35

JOHANNA SCOTT.
